UNITED STATES PATENT OFFICE.

SAMUEL F. WOODSMALL, OF TWIN FALLS, IDAHO.

SHOE-SHINING MACHINE.

1,142,924.

Specification of Letters Patent. Patented June 15, 1915.

Application filed August 30, 1913. Serial No. 787,503.

To all whom it may concern:

Be it known that I, SAMUEL F. WOODSMALL, a citizen of the United States, residing at Twin Falls, in the county of Twin Falls and State of Idaho, have invented certain new and useful Improvements in Shoe-Shining Machines, of which the following is a specification, reference being had to the accompanying drawings.

This invention relates to new and useful improvements in shoe shining machines, the object of the invention being to provide a machine wherein the operating mechanism is located within a casing and is actuated by means of a coin operated switch which connects the operating mechanism with any suitable motive power.

Another object of the invention is the provision of a shoe polishing machine operated by electric motive power and having a coin operated switch which connects the operating mechanism of the machine with the motive power.

A further object of the invention is the provision of a shoe shining machine of the above character which will possess advantages in points of efficiency and durability, is inexpensive of manufacture and at the same time is simple in construction and operation.

With the above and other objects in view, this invention consists in the novel features of construction and the combination and arrangement of parts to be hereinafter more fully described, pointed out in the claims and shown in the accompanying drawings, in which—

Figure 1 is a longitudinal sectional view of a shoe shining machine constructed in accordance with my invention. Fig. 2 is a top plan view, the cover of the casing being removed. Fig. 3 is a transverse sectional view taken on the line 4—4, Fig. 1; and Fig. 4 is a detail plan view of the universal connection between the member 92' and the member 123.

Referring more particularly to the drawings, 1 indicates the lowermost portion of the casing at the forward side of which is an upright casing 2 having a suitable slot 3 therin in which the coin is to be inserted to operate the mechanism within the casing 1.

Mounted upon one end of the main shaft 34 is a pulley 35 around which is arranged a belt 36, said belt extending upwardly to the motor 16 to which power is supplied

through the medium of the knife switch arranged in the casing 2 and actuated through the medium of the handle 10. In the upper end of the casing 2, it will be noticed that an emergency slot 38 is provided, and arranged at the inner end of the slot 3 is a magnet 39 which is adapted to draw bogus coins into the slot 38 to prevent them from entering the tube 4 to operate the machine. Arranged within the bottom of the casing 1 are a plurality of supporting members 40 in which the shaft 34 is adapted to rotate. Arranged within the casing 1 and secured to the bottom thereof by means of the screw bolts 41 is the base member 42 which is constructed of metal or any other suitable material and is provided with a recess 43 and further provided with a longitudinal opening 44 through which the shaft 34 is adapted to extend and rotate.

Arranged within the recess 43 and mounted for rotation upon the shaft 34 is a gear 45 which is adapted to mesh with a small gear 46 mounted upon a longitudinal shaft 47. Formed integral with the gear 46 is a beveled gear which meshes with the gear 48 formed upon the lower face of the rotating casting 50. The casting 50 is rotatably mounted upon an upwardly projecting post 51 which is formed integral with the base member 42. Formed on the casting 50 is a large gear 52 which is rotatably mounted within a suitable casing 53, said casing comprising the body portion 54, the medial portion of which is provided with a circular downwardly extending curved flange 55, having an annular rib 56 at its lower end which engages over a cut away portion 57 of the base 42. Suitable bearings 58 are mounted within the grooves formed in the lower ends of the member 55 and the shoulder 59 of the base 42 whereby the casing 53 may be readily rotated upon the base 42.

The body portion 54 of the casing 53 is provided upon its lower face and adjacent its outer edge with an annular series of teeth 60 which are adapted to mesh with a gear 61 mounted upon the main shaft 34 whereby said casing will be readily rotated upon the rotation of the shaft 34. A cover plate 62 is provided having a central opening to receive the upwardly extending post 51, said cover plate being mounted upon an annular shoulder 63 formed upon the upper face of the body member 54 and securely held in position by means of the set screw

2

64. The cover plate 62 is provided upon one side thereof with an offset portion 65 in which is mounted a transverse shaft 66, the lower end of which is mounted in a suitable bearing formed in the upper face of the body portion 54. Rotatably mounted upon the lower end of this shaft is a gear 67 which is adapted to mesh with a similar gear 68 mounted upon a stub shaft 69 and which in turn meshes with the large gear 52 arranged within the casing so that motion may be readily imparted to a beveled gear 70 which is mounted upon the upper end of the shaft 66.

10 65 Formed integral with the rotatable casing 53 is an angularly projecting sleeve member 71 having an offset angular portion 72 formed at the upper end thereof and upon which is mounted a casting 73. An angularly disposed shaft 74 is provided, the lower end of which is rotatably mounted in a suitable bearing at the lower termination of the arm 71 and the upper end thereof is mounted in a suitable bearing in the casting 73. Rotatably mounted upon the lower end 20 of the shaft 74 and engaging the beveled gear 70 is a similar gear 75 which is adapted to impart motion to the shaft 74 and rotate the gear 76 at the upper end of the shaft. 25 30 The gear 76, mounted upon the upper end of the shaft, is adapted to mesh with a double faced gear 77 which is rotatably mounted within the upper end of the sleeve and one of the central spindles thereof being 35 40 45 50 55 60 65 rotatably mounted within the upper face of the casting 73. The arm 71 is provided at its upper end and upon the inner periphery thereof with an annular groove 78 in which is rotatably mounted the annular rib 79 formed upon the downwardly projecting end portion of the angular sleeve 80, whereby said sleeve is rotatably mounted upon the upper end of the arm 71. Removably secured to the upper end of the arm 71 and provided with an inwardly extending rib portion 81 is a removable plate 82 to one end of which is secured one end of a coil spring 83, the other end of said spring being secured to an upwardly projecting portion formed upon the outer end of the sleeve 80.

As clearly illustrated in Fig. 2, the upper face of the double gear 77 is adapted to mesh with the beveled gear 85 which is mounted upon the longitudinal shaft 86 arranged within the horizontal portion of the sleeve 80. A second gear 87 is mounted upon the shaft 86 opposite the gear 85 and is adapted to mesh with a similar gear 88 which is disposed in a horizontal position and mounted upon the lower end of the shaft 89 which is arranged within the upright portion of the sleeve 80. The upper end of the vertical portion of the sleeve 80 is provided with an enlargement 90 having an outwardly extending annular flange 91 upon

which is mounted the lower end of a rotatable casing 92. Arranged between the lower end of the casing 92 and the annular flange 91 are a plurality of ball bearings 93 whereby any friction is prevented between the casing and the upper end of the sleeve. The casing 92 is securely held in position upon the upper end of the sleeve by means of an internally threaded ring 93 which is removably engaged with the lower end of the casing 92 and is provided with an inwardly extending flange 94 which engaged beneath the flange 91 to prevent the removal of the casing 92.

Removably mounted upon the upper end 30 of the casing 92 and adapted to close the upper end of the same is a closure plate 95 which is securely held in position by means of the set screws 96. A division plate 97 is arranged within the casing 92 and the outer edge thereof is adapted to be mounted upon an annular shoulder 98 formed within the casing 92. The upper end of the shaft 89 is mounted in a suitable bearing formed in the removable plate 95 and mounted upon this shaft and arranged within the chamber formed between the plates 95 and 97 is a large gear 99. Mounted on the shaft 89 and arranged within the lower portion of the casing 92 is a small gear 100 which is adapted to mesh with a somewhat larger gear 101 mounted upon a vertical shaft, the ends of which are mounted in suitable bearings formed in the enlarged portion 90 and the division plate 97. This gear 101 is 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 ally mounted upon the upper end of a movable standard 110. The lower end of the standard 110 is provided with a substantially rectangular bore 111 adapted to receive the upper rectangular end 112 of the post 51 so that the casting 108 may be raised and lowered to any desired position and securely retained in such position by means of a set screw 113 which is carried by the lower tubular end of the standard 110 and adapted to engage the rectangular portion 112 of the post 51. 70

Mounted upon the end of the main shaft 34 adjacent the pulley 35 is a beveled gear 114 which is adapted to mesh with a similar gear 115 mounted upon the lower end of a vertically disposed shaft 116. Supported in one side of the casing 1 and projecting outwardly at an angle thereto is a casting 117 which is provided with a central opening 118 and with a longitudinal bore 119 adapted to receive the upper end of the shaft 116. Mounted upon the upper end of the shaft 116 and arranged within the opening 118 is a gear 120 which corresponds to the gear 45 carried by the main shaft 34 and arranged within the opening 43 formed in the base member 42. It will be readily noted from the showing illustrated in Fig. 2, that the casing 53' which is mounted upon the side of the casting 117 is constructed similar to the casing 53 rotatably mounted upon the base 42. In this casing is the large gear 52' which is adapted to mesh with a train 85 of gears 121 rotatably mounted within the vertical portion of the sleeve 80'. The casing 53' is also provided upon its outer face with a series of teeth 60' which are adapted to mesh with a gear 122 mounted upon the shaft 116 whereby motion may be readily imparted to the casing. 90

The horizontal portion of the sleeve 80' is formed in two sections 123 and 124, the meeting ends of said sections being pivotally connected, as shown at 125 whereby the section 124 may be raised and lowered regardless of the position of the section 123. A coil spring 126 is provided, one end of which is secured to the section 123 and the other end 50 thereof secured to the section 124 so as to assist in retaining the brush members 127 which are carried by the movable section 124 into engagement with the boot or shoe arranged within the casing to be polished. 110

The casing 92' which is mounted upon the outer end of the movable portion 124 of the arm is constructed similar to the casing 92 mounted upon the vertical portion of the sleeve 80 whereby the casing 92' is rotatably mounted upon the outer end of the movable portion 124 of the sleeve and arranged therein are the several gears which impart motion to the rotary brush members 127. It will be readily apparent from the drawings 60 that the coil springs 126 and 83 are adapted

to normally retain the brush members 105 and 127 in engagement with the tops and side portions of the boot or shoe. It will be noted that throughout the several parts of the operating mechanism arranged within the casing 1 a plurality of oil cups 128 are provided which communicate by means of the tubes 129 to various bearings which are kept well lubricated by the maintenance of oil within the cups 128. 75

From the above description taken in connection with the accompanying drawings, the operativeness of my device will be readily apparent taken in connection with the following explanation thereof. When a person desires to have his or her boot or shoe cleaned and polished, the foot is inserted through the opening 106 and rested upon the upper flat face of the casting 108. A nickel or other coin which is designed to operate 80 the machine is inserted in the mechanism which controls the passage of the current to the motor 16, so that a current may be supplied to the motor 37. As the current is supplied to the motor, the shaft 34 is rotated 85 imparting motion to the casing 53 and to the brushes 105 through the various shafts and gearings carried by the casing. Motion is also imparted to the brush members 127 through the various gear members carried 90 by the casing 53'. As the shaft 34 is rotated, the casing 53 will be rotated moving the sleeve 80 around the boot or shoe, the coil spring 83 normally retaining the brushes in engagement with the shoe so that said 100 brush members will readily act thereon. It will also be apparent that the coil spring 126 will materially assist in retaining the brush members 127 into engagement with the shoe so that the toe portion of the shoe may be 105 quickly and readily cleaned, blacked and polished.

It will be apparent that while the brushes 105 are in the position diametrically opposite that of Fig. 2, the brushes 127 will also be in a position diametrically opposite the position illustrated in Fig. 2, thus permitting the arm 124 to pass beneath the arm 80. 110

It will be apparent from the accompanying drawings that as the shaft 34 is rotated, 115 the operating shaft 33 will also be rotated to impart motion to the vertically disposed shaft 27, said shaft upon which is mounted the worm gear 26 will rotate the cam 24 and reciprocate the pitman 21. 120

It will be noted that I have provided three brushes 104, and three brushes 127. One of these brushes 104 is in engagement with the blacking in container 107. The other two brushes, however, are not in such engagement. 125 The same is true of the brushes 127. One of the brushes 104 and one of the brushes 127 is designed to clean the shoe of dirt, another of the brushes 104 and 127 is designed to apply blacking to the shoe, and the third 130

brush of each set of brushes is designed to polish the shoe after the blacking is applied. The gears whereby the rotation of the set of brushes around a central axis is secured, are so proportioned that upon the first movement of the brushes 104, for example around the shoe, the cleaning brush will be applied to the shoe. Upon the next rotation of the brushes around the shoe the daubing brush will be applied thereto, and upon the third rotation around the shoe the polishing brush will be engaged therewith. At the end of this period the motor will be deenergized as previously stated. The same is true of the brushes 127. Both the brushes 104 and 127 describe closed paths, the brushes 104 describing a path around the shoe support and in a horizontal plane, while the brushes 127 describe a path around the shoe support in a vertical plane.

From the above description taken in connection with the accompanying drawings, it will be readily apparent that I have provided a shoe polishing machine wherein a boot or shoe may be quickly and readily polished, the operation being carried out by dropping a nickel in the slot 3 and actuating the handle member 10 connecting the operation mechanism within the casing 1 with the motor 16. It will be understood that as soon as the boots or shoes have been cleaned and polished, the operating mechanism will be automatically cut off by relieving the pressure of the movable contacts upon the knife 9, this cutting off the circuit and permitting the knife to return to its normal position. It will also be apparent that my device is extremely simple in construction and can be manufactured at comparatively low cost.

While I have shown and described the preferred form of my invention, it will be obvious that various changes in the details of construction and in the proportions may be resorted to for successfully carrying my invention into practice without sacrificing any of the novel features or departing from the scope of the appended claims.

What I claim is:—

1. A device of the class described including a casing, a base member therein, a rotatable casing upon the base, an angularly disposed arm formed integral therewith, an angular sleeve rotatably mounted upon said arm, rotary brush members carried by the upper end of said sleeve, a second base arranged within the casing and disposed at one side thereof, a rotatable casing mounted thereon, a sectional sleeve formed thereon, and rotary brush members carried by the outer ends of the sectional sleeve, as and for the purpose set forth.

2. A device of the class described including a casing, a base member mounted thereon, a rotatable casing upon the base, a gear

mounted for rotation within the casing, an angularly disposed arm formed integral with the base, an angular sleeve rotatably mounted upon said arm, rotary brush members mounted upon the upper end of the sleeve, means connecting the gear with the rotary brush members whereby to impart movement to the brush members, a second base arranged within the casing and disposed at one side thereof, a rotatable casing carried thereby, a gear within the casing, a sectional sleeve formed on the casing, rotary brush members carried by the sectional sleeve, and means connecting said gear with the brush members, whereby to impart rotary movement to the brush members, as and for the purpose set forth.

3. In a shoe blacking apparatus, a vertically disposed brush movable in a circular horizontal closed path whereby to engage the side faces of the shoe, and a plurality of brushes movable in a circular vertical path whereby to engage and pass over the upper face of the shoe.

4. In a shoe blacking apparatus, a vertically disposed brush movable in a horizontal closed path, means for supporting a shoe within said path, means for forcing said brush against the shoe so supported to conform to the outline thereof, and a brush movable in a circular path in a vertical plane and around the toe portion of said shoe support.

5. In a shoe blacking apparatus, a shoe support, a base rotatable relative to said shoe support, said base having a laterally projecting arm, a rotatable head mounted upon the arm, a plurality of brushes each rotatable upon and with relation to the head, means for rotating the base, the head and said brushes, whereby to carry the brushes around and in contact with a shoe mounted upon the support and to independently rotate the head and independently rotate the brushes with relation thereto.

6. In a shoe blacking machine, a foot support, a member rotatable around said foot support, a rotatable brush support mounted upon said member, three brushes carried thereby, a font with which one of said brushes engages to supply blacking thereto and disposed between the brush with which it coacts and the other brushes, and means for rotating the brush support to carry said brushes successively into contact with a shoe mounted upon said support.

7. In a shoe blacking apparatus, a vertically disposed brush movable in a circular horizontal path whereby to engage the side face of the shoe, a brush movable in a circular vertical path whereby to engage and pass over the upper face of the shoe, and means for causing one of said brushes to intercept the path of movement of the other brush at the time when the other brush is

out of the path of movement of said first named brush.

8. In a shoe blacking apparatus, a shoe support, a base rotatable with relation to the shoe support and having a laterally projecting arm, an arm angularly disposed with relation to the first named arm and rotatably mounted thereon, a head rotatably mounted upon the second named arm, a plurality of rotatable brushes mounted upon the head, a spring resisting the rotation of the second named arm relative to the first

named arm and yieldably holding the second named arm directed toward the shoe support, and means for rotating said base, the head, and said brushes at different relative speeds.

In testimony whereof I hereunto affix my signature in the presence of two witnesses.

SAMUEL F. WOODSMALL.
